DESIGN FOR WRAPPING PAPER OR SIMILAR ARTICLE

Homer M. Sinclair, Holyoke, Mass.

Application July 14, 1937, Serial No. 70,434

Term of patent 7 years

To all whom it may concern:

Be it known that I, Homer M. Sinclair, a citizen of the United States, residing at Holyoke, in the county of Hampden and State of Massachusetts, have invented a new, original, and ornamental Design for Wrapping Paper or Similar Article, of which the following is a specification, reference being had to the accompanying drawing, forming part thereof.

Fig. 1 is a plan view of a sheet of wrapping paper showing my new design.

I claim:

The ornamental design for wrapping paper or similar article, as shown.

HOMER M. SINCLAIR.
